[57] CLAIM

I claim the ornamental design for a heated food product bin, as shown and described.

DESCRIPTION

FIG. 1 is a perspective view of a heated food product bin showing my new design;

FIG. 2 is a top plan view thereof;

FIG. 3 is a side elevational view thereof;

FIG. 4 is front elevational view thereof;

FIG. 5 is a rear elevational view thereof;

FIG. 6 is a perspective view of a second embodiment of a heated food product bin showing my new design;

FIG. 7 is a top plan view thereof;

FIG. 8 is a side elevational view thereof;

FIG. 9 is a front elevational view thereof;

FIG. 10 is a rear elevational view thereof;

FIG. 11 is a perspective view of a third embodiment of a heated food product bin showing my new design;

FIG. 12 is a top plan view thereof;

FIG. 13 is a side elevational view thereof;

FIG. 14 is a front elevational view thereof;

FIG. 15 is a rear elevational view thereof;

FIG. 16 is a perspective view of a fourth embodiment of a heated food product bin showing my new design;

FIG. 17 is a top plan view thereof;

FIG. 18 is a side elevational view thereof;

FIG. 19 is front elevational view thereof; and,

FIG. 20 is a rear elevational view thereof.

The surfaces or portions of the article not shown in the drawings or described in the specification form no part of the claimed design.
